UNITED STATES PATENT OFFICE.

MELVIN L. BLACKBURN, OF BELLAIRE, OHIO, ASSIGNOR TO THE BELLAIRE GOBLET COMPANY, OF SAME PLACE.

DESIGN FOR A DISH OR TABLE-WARE.

SPECIFICATION forming part of Design No. 16,941, dated October 19, 1886.

Application filed July 12, 1886. Serial No. 207,844. Term of patent 3½ years.

To all whom it may concern:

Be it known that I, MELVIN L. BLACKBURN, of Bellaire, in the county of Belmont and State of Ohio, have invented a new and original Design for Table-Ware; and I do hereby declare the following to be a full, clear, and exact description thereof, reference being had to the accompanying drawings, forming part of this specification, in which—

10 Figure 1 is an end view of a dish or vessel illustrating the design. Fig. 2 is an end view thereof.

15 The leading features of the design consist in a dish or vessel representing in form a railway-car having imitation wheels, and in the ornamentation of such a car.

20 The drawings represent the vessel in form of a railway-car having representations of wheels 3 at the front and rear. These wheels appear as if embedded in or formed integral with webs 4, which depend from the bottom of the car at the sides thereof, and which are provided with raised figures 5, representing the springs and bolsters of the car. The sides 25 of the car, near the base, are ornamented with a raised prismatic figure, 6, and the car-windows are simulated by plain unfigured spaces 7, inclosed and defined by raised panels 8. In like manner the doors at the end of the car are

simulated by plain portions 10, appearing as 30 if made integral with the part of the dish representing the car-body, and being inclosed by defining panels 11.

The roof of the car has a series of plain portions, 9, representing the ventilating-windows, 35 and interposed figured panels, which define the windows.

I claim as my invention—

1. The design for table-ware, consisting of a dish representing a railway-car having parts 3 40 and 4, simulating car-wheels, as shown and described.

2. The design for table-ware, consisting in a dish which represents a railway-car having portions 7, representing windows, raised panels defining them, and a prismatic figured portion, 6, at the bases of the portions 7, as shown 45 and described.

3. The design for table-ware, consisting in a dish the body of which represents a railway- 50 car, together with a lid representing the roof of the car, as shown and described.

In testimony whereof I have hereunto set my hand this 25th day of June, A. D. 1886.

MELVIN L. BLACKBURN.
